CHUSETTS, A CORPORATION OF MASSACHUSETTS.

MOTOR-CYCLE FRAME.

1,101,435.

Specification of Letters Patent.

Patented June 23, 1914.

Application filed May 17, 1912. Serial No. 697,926.

To all whom it may concern:

Be it known that we, CARL O. HEDSTROM and CARL J. GUSTAFSON, a citizen of the United States and a subject of the King 5 of Sweden, respectively, residing at Springfield, in the county of Hampden, State of Massachusetts; have invented certain new and useful Improvements in Motor-Cycle Frames, of which the following is a description, reference being had to the accompanying drawing, and to the figures of reference marked thereon.

Our invention relates to spring frames for motor cycles.

15 The objects of the invention are to provide improved spring supports for both the rear and front wheels, which will absorb the shocks; to reinforce the main spring on its rebound by means of a lower leaf; to provide a stop on the spring which will, in the event of the main spring breaking, prevent the spring from slipping out of the shackle; also to provide the shackle with upper and lower cushions for the spring; also to 20 prove the construction of the shackle.

These objects we accomplish by the construction shown in the accompanying drawing, in which,—

Figure 1 shows a perspective of a motor 30 cycle frame with our improvements applied; Fig. 2 is an enlarged perspective of one of the rear springs and shackles; and Fig. 3 is a side view of the front spring and shackle.

35 1 designates the frame as a whole, provided at its front with the usual steering head, in which is mounted the spindle 3 of the steering fork 2. This fork 2 is firmly braced by a divided rigid truss 4, the lower 40 ends of which are secured to the lower ends of the fork 2, while its upper portions are connected to the crown of fork 2, the upper arms of the truss converging into a single post 6, which is secured to the upper end 45 of the fork spindle 3 by an arm 7. To the lower ends of the fork 2 are pivoted the bell crank levers 8 in the angles of which are mounted the bearings of the front wheel 9. From the rear arms of the bell crank 50 levers the levers 10 extend upwardly, and are united at the upper ends by two cross bolts 11, 12, which form with the upper ends of the levers 10, a shackle for the spring 13.

This spring 13 extends forwardly from the crown of the fork 2, to which it is rigidly secured, through the shackle, and its middle leaf is curved downwardly and rearwardly and formed with an eye 14, through which the lower cross bolt 12 extends. The upper leaf 15 of the spring 13 is rolled into an eye 16, in front of the shackle, and a cross pin 17 extends therethrough and beyond the sides of the shackle to form a stop to prevent the spring from pulling through the shackle in case the spring or its pin 12 should break.

The bottom spring leaf 18 terminates where the middle leaves begin to curve, and forms a reinforce for the main leaf spring on the rebound. This spring leaf 18 is secured at its forward end to the lower cross piece of a clip 19, which embraces the main spring.

Within the shackle is a rubber bumper 20, below the spring 13, while above the spring 13 is a second bumper 21, so that contact of the spring with the bolts 11, 12, is prevented, and noise and shock thereby avoided. The bumper 20 is a block, and has projecting pins 22 at its opposite sides, 80 which prevent it from getting out of place, while the upper bumper 21, is a cylinder, and is mounted on the bolt 11. It will be seen, therefore, that a most effective and noiseless spring support is provided for the 85 front wheel, which receives, and would without such a device, transfer most of the disagreeable shocks and jars due to obstacles and inequalities of the road.

The rear wheel is mounted in bearings 23, 90 at the rear end of a horizontal fork 24, pivoted at its forward end to the lower part of the rear end of the frame, as shown at 25, and from the rear ends of the fork 24 extend upwardly the lever rods 26, 26, pivoted at their lower ends to the upper ends of the bearings 23; and provided at their upper ends with forks or shackles 27. Upper and lower cross bolts 28, 29, extend across these shackles 27, and secure in place the 100 lower ends of an upwardly extending yoke 30, which connects the two shackles 27, and straddles the upper part of the rear wheel. A pair of springs is employed at the rear, each spring having two middle leaves in 105 stead of one, as in the front spring.

The forward ends of the rear springs 13 are secured to a rearwardly extending arched bracket 32, firmly secured as shown, to the rear upper end of the frame. These springs 13 extend through the shackles 27, and are curved downwardly and thence forwardly, to the lower shackle bolts 29.

The upper spring leaves have the stop pins 17, and the lower spring leaves are connected to the clips 19. The same bumpers 20, 21, are also employed in the rear shackles 27. In striking any obstruction or inequality, the rear wheel will move upwardly on its fork axis 25, and in so doing 15 the rods or levers 26 will raise the connected shackles 27, and the curved ends of the springs. The bumpers 20, 21, will take up and neutralize all shocks due to extreme movements of the springs. In the rebound or return movements of the parts, the lower leaves 18 of the springs will absorb the shock 20 and stiffen the main leaves of the springs.

When the wheel strikes an obstruction, if it is a slight one the loop part will take up 25 the shock. If the shock is a great one beyond the capacity of the loop, and the bumper 20 strikes the under side of the spring, then the shock is transferred to the entire body of the spring. On the rebound, 30 the bumper 21 acts as a shock absorber, and the lower leaf of the spring reinforces the body thereof, or in effect acts in opposition thereto, preventing too great travel of the loop, and, therefore, danger of crystalliza- 35 tion.

Having thus described our invention, what we claim as new and desire to secure by Letters Patent, is:—

1. A motorcycle frame including a main 40 spring, a movable wheel support, means for connecting said spring to said support, said spring comprising a central leaf to which said support is connected, an upper leaf for reinforcing said central leaf on the upward movement thereof, and a lower leaf for reinforcing said central leaf on the rebound.

2. A motorcycle frame including a leaf 50 spring, a movable wheel support, said spring comprising a plurality of spring leaves, the center leaf of which extends beyond the outer ends of the spring leaves above and below the same, means for connecting said central spring leaf to said support, said central spring leaf being bent backward and attached to said connecting means at a point in rear of the ends of the upper and lower spring leaves.

3. A motorcycle frame including a leaf 60 spring, a movable wheel support, said spring comprising a plurality of spring leaves, the center leaf of which extends beyond the outer ends of the spring leaves above and below the same, means for connecting said central spring leaf to said support, said central 65 spring leaf being bent backward and at-

tached to said connecting means at a point in rear of the ends of the upper and lower spring leaves, said connecting means including a shackle attached to the free end of said central spring leaf, a bumper carried by 70 said shackle above and below said spring leaves and in rear of the ends of the upper and lower spring leaves.

4. In a vehicle frame, a spring having its free end curved back upon itself, a shackle 75 through which the spring passes with its free end secured therein, bumpers mounted in the shackle above and below the spring, a movable wheel support or bearing below the spring, and a connection between the wheel 80 support and the shackle.

5. In a vehicle frame, a spring having its free end curved back upon itself, a shackle 85 through which the spring passes with its free end secured therein, bumpers mounted in the shackle above and below the spring, a movable wheel support or bearing below the spring, a connection between the wheel support and the shackle, and a stop on the spring adapted to engage the shackle in case 90 the spring should break.

6. A motorcycle frame including a shackle, a leaf spring rigidly attached to said frame and having its free end extending through said shackle, the free end of 95 said spring being curved under the shackle and secured thereto, a stop on the spring adapted to engage the shackle if the spring should break, a movable wheel support, and rods for connecting the shackle with the 100 support.

7. In a motor cycle frame, a longitudinally extending leaf spring having its free end curved under said spring comprising a plurality of leaves placed one above the other, the top leaf of the spring having an 105 eye, a stop pin passed through said eye and having projecting ends, a similar eye on the lower leaf, a clip embracing the middle members of the spring with its lower cross piece secured to said eye on the lower spring leaf, a shackle through which the spring projects with its free end secured thereto, an upwardly movable wheel support, and rods connecting the wheel support and 115 shackle.

8. A motorcycle including a frame, a bracket rigidly attached to said frame, a pair of rearwardly extending spaced parallel leaf springs rigidly fixed to said bracket 120 and located on opposite sides of the wheel, a shackle connected to the free end of each spring, means for connecting the shackles, a movable wheel support, and means for connecting said support with the shackles. 125

9. A motorcycle including a frame, a bracket rigidly attached to said frame, a pair of rearwardly extending spaced parallel leaf springs rigidly fixed to said bracket and located on opposite sides of the wheel, 130

each spring being bent backwardly, a shackle connected to the free end of each spring, said shackle for each spring having a bumper above and below the spring, an arch for connecting said shackles, a movable wheel support, and devices for connecting said movable wheel support to said shackles, said movable wheel support being connected with the frame for guiding the up and down movements thereof relative to said frame.

10. In a motor cycle frame, a pair of rearwardly extending springs having their free ends curved under, shackles through which the springs pass with their free ends secured therein, bumpers on the shackles above and below the springs, an arch connecting the shackles, a pivoted forked wheel support below the springs, and rods connecting the two shackles with the arms of the said wheel fork.

11. In a motor cycle frame, a pair of rearwardly extending main springs having their ends curved under, connected shackles through which the springs pass with their free ends secured therein, stops on the springs in rear of the shackles, a movable fork for the rear wheel, and rods connecting the shackles with the arms of the said fork.

12. The combination in a motor cycle frame, of a rearwardly extending pivoted fork for the rear wheel, a pair of rearwardly extending springs, rods extending upwardly from the fork arms and having connected shackles at their upper ends to which the free ends of the springs are connected,

bumpers in the shackles for the springs, and stops on the springs in rear of the shackles.

13. In a motor cycle frame, a pair of rearwardly extending main springs having their free ends curved under, a rearwardly extending vertically movable fork for the rear wheel, rods extending up from the fork arms and provided at their upper ends with shackle-forming yokes, embracing the springs and provided with lower bolts, to which the free ends of the springs are connected, and upper bolts above the springs, and an arch between the shackles and secured thereto by the inner ends of said bolts.

14. A spring for vehicle frames having its main leaf portion bent back upon itself, a bottom leaf forming a rebound spring, and a shackle with bumpers mounted therein above and below the spring.

15. A main spring having its free end bent back upon itself, a shackle through which it passes, with its free end secured thereto, a lower leaf secured to a clip surrounding the main portion and formed to act in opposition to the main spring on the rebound, and an upper leaf provided with a stop.

In testimony whereof, we affix our signatures in the presence of two witnesses.
